UNITED STATES PATENT OFFICE.

CHARLES T. HAWLEY, OF HOPEDALE, MASSACHUSETTS, ASSIGNOR TO DRAPER COMPANY, OF HOPEDALE, MASSACHUSETTS, A CORPORATION OF MAINE.

SPINNING-FRAME.

SPECIFICATION forming part of Letters Patent No. 687,527, dated November 26, 1901.

Application filed August 26, 1901. Serial No. 73,381. (No model.)

To all whom it may concern:

Be it known that I, CHARLES T. HAWLEY, a citizen of the United States, and a resident of Hopedale, county of Worcester, State of Massachusetts, have invented an Improvement in Spinning-Frames, of which the following description, in connection with the accompanying drawings, is a specification, like characters on the drawings representing like parts.

This invention has for its object the production of novel means for effecting the spinning of yarn upon a yarn-receiver or bobbin in such a way that a preliminary winding or bunch will be laid and thereafter a main or service winding to complete the yarn mass.

To this end my invention has more particular relation to the builder-motion of a spinning-frame, and the various novel features of construction, arrangement, and operation embodied in my present invention will be fully described hereinafter, and particularly pointed out in the following claims.

Bobbins or filling-carriers provided with a bunch and a service winding of yarn are principally used in the shuttles of automatic filling-replenishing looms of the "feeler" type, the filling being replenished by or through the action of a feeler when the yarn has woven off down to the bunch in a manner well known to those skilled in the art.

Figure 1 is a front elevation of one end of a spinning-frame, showing the builder-motion with one embodiment of my invention applied thereto. Fig. 2 is a transverse section on the line 2 2, Fig. 1, looking toward the left. Fig. 2^a is an enlarged detail in side elevation of a portion of the mechanism shown in Fig. 2, to be referred to. Fig. 3 is a view in elevation of a yarn-receiver or bobbin with a preliminary winding or bunch upon the barrel thereof near its head or base, the outline of the filled bobbin being indicated by dotted lines. Fig. 4 is a greatly-enlarged plan view of the builder-motion, including the builder-arm and the novel features of my invention coöperating therewith, the actuating or traverse cams being omitted. Fig. 5 is a transverse section on the line 5 5, Figs. 2 and 4, looking in the direction of the arrow

5 5, but on a scale corresponding to Fig. 4. Fig. 6 is an enlarged detail of a portion of the builder-arm looking toward the right, Fig. 4, showing the bunch and service winding cam-followers. Fig. 7 is an enlarged plan view, 55 partly broken out, of a detent-pawl and its carrier, illustrated in Fig. 2 as mounted on the follower rock-shaft and omitted in Fig. 4 for the sake of clearness, said pawl forming part of the means for governing automatically the change from bunch to main or service winding. Fig. 8 is an inner side elevation of one of the component members of such means to be described; and Fig. 9 is an outer face view of a coöperating member, the members shown in Figs. 8 and 9 being illustrated in plan in Fig. 4.

Referring to Figs. 1 and 2, the end frame A, spindle-rail R^X, on which are mounted the rotatable sleeve-whirl spindles S, the vertically-reciprocating ring-rail R, provided with a ring R' for each spindle, the cam-shaft C^X, the builder-arm B^X, fulcrumed at B' on the usual samson A^X, and the winding mechanism mounted on the builder-arm may be and are all of usual and well-known construction, the builder-motion, which includes the building-arm and winding mechanism, effecting the traverse of the ring-rail to lay the yarn upon the yarn-receiver or bobbin B. The worm-shaft m² of the winding mechanism is actuated in usual manner by coöperation of the pawl m with the ratchet or pick wheel m' by intermittent engagement of the pawl with an actuator m^X during the laying of the yarn 85 upon the yarn-receiver or bobbin B, the worm-shaft rotating the drum m³ and gradually letting off the chain m⁴, connected in usual manner with the rocker R¹⁰, which operates the lifter-rods L, one of which only is shown in 90 Fig. 1. In said figure the apparatus is shown as effecting the winding of the bunch, and during such winding the actuator m^X preferably will not engage and operate the pawl m, so that the ring-rail does not rise a little 95 higher at the upper end of each stroke, as it does later when the filling is being laid to form the main or service winding and with the actuator m^X intermittently engaging the pawl m. The bunch or preliminary winding 100

w (see Fig. 3) is thus wound with a short traverse, and the main or service winding *w*^x, Fig. 3, is laid with the filling-wind and with a longer traverse, and to effect the two windings I have herein provided two separate actuating devices to coöperate with the builder-arm. In my present invention one of said actuating devices is thrown out of operation and coöperation of the other device with the builder-arm is effected at the proper time automatically, and novel means are provided for governing the change from one to the other actuating device. The actuating devices are herein shown as two cams *P M*, fast upon the cam-shaft *C*^x, the former actuating the builder-motion during the laying of the preliminary winding or bunch and the latter during the laying of the main or service winding of yarn upon the yarn-receiver, and herein the cam *M* is shown as a heart-cam of usual construction and adapted to lay the yarn with the filling-wind, one complete revolution of the cam effecting a complete reciprocation of the ring-rail. The bunch-winding cam *P*, however, is shown as having a plurality of high and low points, (see Fig. 2,) one of the low points being shown at *p* and the corresponding high point at *p*^x, rotation of the cams being effected in the direction of the arrow 10, Fig. 2, and consequently one complete rotation of the cam *P* will effect a number of complete reciprocations of the ring-rail, corresponding to the number of corresponding high and low points thereon, the bunch being laid with a corresponding number of traverses.

The builder-arm is provided with a laterally-offset bracket *B*^y, (see Figs. 4, 5, and 6,) provided with a boss *b*^y to form an outer bearing for a short rock-shaft *d*^y, the inner end of the rock-shaft being extended through and having a bearing in a depending ear *b*^z on the builder-arm. (Shown in Fig. 2.) The said rock-shaft has rigidly secured to it two rocker-arms *d d'*, provided with laterally-extended rolls or followers *p*²⁰ *m*²⁰ to coöperate one at a time with the cams *P M*, respectively, the followers being set at an angle to each other on the rock-shaft, as best shown in Figs. 1 and 6. The follower *p*²⁰ is adjustably mounted in the arm *d*, as shown in Fig. 6, having its stud 12 extending through a longitudinal slot 13 in the arm and is rigidly held in adjusted position by a set-nut 14. This adjustment enables the location of the bunch to be adjusted on the yarn-receiver or bobbin, as the adjustment of the follower toward the rock-shaft *d*^y will cause the bunch to be wound higher up on the bobbin, whereas opposite adjustment of the follower will have the effect of laying the bunch nearer the head of the bobbin. At its inner end the rock-shaft *b*^y has rigidly secured thereto by set-screws 15 a hub *d*², having a peculiarly-shaped upturned ear *d*³, (see Fig. 2^a,) provided with a lip or flange *d*⁴, a portion of which is eccentric with a stud *d*⁵, secured to the ear and extended laterally therefrom, said stud serving as a fulcrum for

a pawl-carrier *d*⁶, (see Figs. 2, 5, and 7,) the pawl-carrier being shown as an upturned arm having a lateral offset *d*⁷, terminating in a hub *d*⁸, in which hub is mounted a stud *d*⁹, (see Fig. 7,) the stud having rigidly secured to it a pawl *d*¹⁰. A coiled spring *s*², Fig. 7, surrounds the stud *d*⁹, and at one end it is secured to the hub *d*⁸, the other end of the spring being attached to a sleeve *d*¹², pinned to the stud. The winding of the spring is such that the back of the pawl is normally maintained against the end of a set-screw 16, mounted in an ear 17 of the hub *d*⁸ and held in adjusted position by a check-nut 18.

The pawl-carrier *d*⁶ is provided with a locking-dog *d*¹³, Figs. 5 and 7, for a purpose to be described, and the lower end of the pawl-carrier, as shown clearly in Fig. 2^a, is made to fit the curved portion of the flange *d*⁴, while a tangent portion or shoulder 19 on the pawl-carrier adjacent its fulcrum *d*⁵ is adapted to at times coöperate with the straight or tangent portion 20 of the said flange to limit downward movement of the pawl-carrier relative to its supporting-hub *d*².

The cam-shaft *C*^x has loosely mounted upon it a ratchet-wheel *C*, prevented from movement longitudinally in one direction by a collar 22, fast on the cam-shaft, and adjacent the said ratchet-wheel a cam-disk *E* is also mounted on the cam-shaft to rotate therewith, but longitudinally movable thereupon, and herein I have shown the disk as having on its outer face relatively to the ratchet *C* a lateral lug *e*, which is extended between two ears 23, secured to or forming part of a collar 24, rigidly secured to the cam-shaft, the sliding connection between the lug *e* and ears 23 permitting longitudinal movement of the disk *E* on the shaft and also effecting its rotation therewith, a spring *S*³, coiled around the shaft between the hub of the disk *E* and the collar 24, acting normally to press said disk toward the ratchet *C*. A segmental cam *e'* is formed on the inner face of the disk concentric with the shaft *C*^x, the leading end of the cam being inclined, as at *e*², Fig. 8, from the face of the disk to the top or parallel face of the cam to permit a coöperating follower-lug *c*' on the adjacent face of the ratchet *C* to pass from the face of the disk *E* up onto the cam *e'*, when relative rotative movement of the ratchet and disk is effected, the shape of the follower *c*' being best shown in full lines, Fig. 4, and dotted lines, Figs. 5 and 9. Referring to Figs. 4 and 5, wherein the follower *c*' is shown as traveling on the flat surface of the cam *e'*, it will be manifest that at such time the disk *E* will be pressed toward the builder-arm against the action of the spring *S*³, and it will also be manifest that when the follower *c*' drops off the abrupt end *e*³ of the cam the said spring will instantly operate to move the disk *E* toward the ratchet *C* as far as the follower *c*' will permit, and when the follower drops from the end *e*³ of the cam it is held between such end and a

rounded lug e^4 , formed on the face of the disk, this lug being shown in Fig. 8.

On its outer face the disk E is provided with a radial rib or trip e^5 , (see Figs. 5 and 8,) the trip in cross-section being substantially triangular, as shown in Fig. 5, and adapted to engage a finger f, adjustably secured at f' to an upturned arm f^x , having at its lower end a rigidly-attached fulcrum-stud f^2 , (see Figs. 4 and 5,) which is mounted in a bearing b^6 , secured to a dropped or depending part b^7 of the builder-arm, a spring s^5 (see Fig. 4) surrounding the rear end of the stud and being attached at one end to the bearing b^6 and at its other end to a sleeve f^3 , pinned to the stud, the spring normally acting to throw the finger f toward the outer face of the disk E. The arm f^x is provided with a notch f^4 to be at times engaged by the locking-dog d^{13} , as clearly shown in Fig. 5, and remembering that this dog is a part of the pawl-carrier d^6 it will be manifest from an inspection of Figs. 2 and 5 that when the dog is in engagement with the notch f^4 the pawl d^{10} will be positioned to coöperate with the ratchet C whenever the builder-arm is raised sufficiently to bring the pawl into the position shown in Figs. 1 and 2.

An arm h, fulcrumed at h^x in an ear a^x on the part A^x of the main frame, is extended laterally therefrom toward the builder-arm, and at its free end is downturned adjacent the peripheries of the ratchet C and disk E, (see Figs. 4 and 5,) and said arm has secured to or forming part of it a notched plate h' , which embraces the periphery of the disk, and a downturned finger h^2 , carried by the arm h, is at certain times brought into the path of movement of a lug c^2 on the outer face of the ratchet C, the movement of the disk E longitudinally of the cam-shaft swinging the arm h on its fulcrum to move the finger or stop h^2 into or out of the path of movement of the said lug c^2 , and when in the path of the lug, as illustrated in Figs. 4 and 5, it will be manifest that when the lug engages the finger rotation of the ratchet will be stopped until the finger is withdrawn from operative position.

Having described in detail the mechanism illustrated in the drawings, the operation of the apparatus will now be described, it being noted that the parts are shown in the drawings in the position they occupy during the formation of the bunch or preliminary winding. The frictional connection between the disk E and the ratchet C acts to rotate the latter unless it is retarded or prevented, and during the winding of the bunch the pawl d^{10} is at each upward stroke of the builder-arm brought into position to engage and stop the rotation of the ratchet, the disk E rotating continuously with the cam-shaft, so that after a predetermined retardation of the ratchet, effected by the intermittent action of the pawl, the follower-lug c' will ride up on the incline e^2 and onto the cam e' , whereupon the disk and ratchet will have been laterally

separated sufficiently to bring the releasing-lug e^5 on the outer face of the disk E into position to act upon the finger f and disengage or release the locking-dog d^{13} from its holding-notch f^4 in the arm f^x , such release of the dog permitting the pawl-carrier d^6 to swing downward on its fulcrum d^5 until the shoulder 19 abuts against the tangent portion 20 of the flange d^4 , thus moving the pawl d^{10} down, so that it cannot engage the ratchet C on the next upward swing of the builder-arm and also releasing the follower rock-shaft d^x . During the winding of the bunch the actuating or traverse cam P is acting upon the follower p^20 . At such time a lug d^{20} , depending from the follower rock-shaft d^x , abuts against a stop 60 (see Fig. 6) on the bracket B^3 . When the rock-shaft d^x is released and before complete change from bunch to service winding takes place, the two followers will to a certain extent coöperate simultaneously with their actuating-cams, and the builder-arm will be actuated by the joint action of such cams, the followers being so set that at the time of release both will be in contact with their respective cams. Thereafter to change automatically the mechanism from bunch to main or service winding the respective followers p^20 m^20 will coöperate with the low point m^20 of the cam M and at or near a low point p of the bunch-winding P, respectively, so that both cams will act upon their followers to throw them in the direction of the arrow 70, Fig. 6, swinging the arm d into upright position and moving the arm d down and the follower p^20 out of coöoperative engagement with its cam, the main winding-cam M thereafter operating through its follower m^20 to effect the movement of the builder-arm, and at such time the arm d will be thrown against a stop 80 (see dotted lines, Fig. 6) on the bracket B^3 . This change of the control of the builder-arm from the bunch-winding cam to the main-winding cam does not take place at the instant that the dog d^{13} is released from its holding-notch, but somewhat after this has been released, as will be manifest from an inspection of Fig. 2, wherein such release is just about to be effected; but it will be seen that the actuating-cams P M are relatively positioned, so that the throw of the follower rock-shaft b^x will not take place until the cam-shaft C^x has made about three-quarters of a revolution from the position shown. Referring to Figs. 4 and 5, it will be seen that while the follower-lug c' is traveling over the flat surface of the segmental cam e' the stop-finger h^2 will be in the path of the lug c^2 and will hold the ratchet C from rotative movement, and the ratchet will be so held until the disk E has turned far enough to permit the follower c to drop off the end e^2 of the cam e' and between such end and the lug e^4 . When this takes place, the spring S^3 immediately acts to move the disk E toward the ratchet, and, as has been described, the arm h will thereby be

swung to move the stop-finger h^2 from engagement with the lug c^2 , and the ratchet will be released and will continue to rotate with the disk E until the main or service winding 5 of the yarn on the yarn-receiver is completed, the ring-rail being raised and lowered once for each complete rotation of the cam M, and during the entire main winding the pawl d^{10} will be out of engagement with the ratchet.

10 It will be remembered that there is a preliminary movement of the pawl away from the ratchet, due to the release of the locking-dog d^{18} from its holding-notch f^4 , and subsequently when the follower rock-shaft d^x is 15 turned to bring the follower m^{20} into operative position the pawl-carrier d^6 will be swung downward still farther. After the winding of the yarn has been completed and the yarn-receiver or bobbin filled the parts will be in 20 position ready for the starting of a new bobbin or set of bobbins. The attendant will then swing the pawl-carrier d^6 upward to bring the locking-dog into engagement with its holding-notch f^4 , thereby swinging the 25 follower rock-shaft d^x to bring the bunch-winding follower p^{20} into position to coöperate with the cam P, and at the same time the pawl d^{10} will be moved into position to coöperate with and intermittently arrest rotative 30 movement of the ratchet C at each upward movement of the builder-arm, and the spring s^2 , which normally holds the pawl d^{10} in position against its adjustable back-stop or set-screw 16, will yield if for any reason the upward movement of the pawl should be interfered with, and thereby prevent any breakage 35 of the parts. This spring also operates, in connection with the adjustable back-stop 16, to regulate the extent of retardation of the ratchet C by or through engagement with the pawl. If the back-stop is set up so that the pawl will come into engagement with the ratchet later as the builder-arm is lifted and leaves it sooner as the builder-arm descends, 40 it will be manifest that the retardation of the ratchet will be less than if the pawl were adjusted, through its back-stop, to engage the ratchet earlier and leave it later in the rise and fall of the builder-arm. The longer each 45 retardation of the ratchet, due to engagement with the pawl, the shorter will be the time which must elapse before the follower-lug c' will be brought into position to coöperate with the cam e' , and consequently the less 50 yarn will be laid in forming the bunch or preliminary winding. Conversely, if the intermittent retardations of the ratchet are shortened it will take a longer time after the beginning of the winding of the bunch to effect 55 engagement of the follower c' and cam e' , and more yarn will be laid in the bunch. Thus I have provided means for automatically regulating the volume of the bunch or preliminary winding, and I have also provided 60 means for automatically resetting the parts after completion of the preliminary winding, so that when the main or service winding is

completed the simple movement of the pawl-carrying arm d^6 into operative position will insure the winding of the bunch when the 70 frame is again started. The resetting referred to is accomplished by means of the stop-finger h^2 and lug c^2 on the ratchet, as thereby the relative angular position of the disk E and ratchet is changed so that they 75 will be properly set relative to each other for the beginning of the bunch winding for the next set of bobbins. The change from bunch-winding to main or service winding is automatically effected, as has been described, by 80 or through the simultaneous action of the two traverse or actuating cams upon their respective followers mounted on the builder-arm at one point in the rotation of the main-winding cam, the follower rock-shaft d^x being at that time free to be rocked. The movement of the follower-lug c' into the space between the heel e^3 of the cam e' and the projection e^4 is effected at the instant the stop-finger h^2 is moved to release the 90 ratchet C, and the latter rotates in unison with the disk E during the main or service winding. When the next bunch winding is started, the first arrest of the ratchet by the pawl d^{10} causes the lug c' to ride up over the 95 projection e^4 and onto the face of the disk E beyond said projection, thus always insuring a given relative angular position of the ratchet and disk at the beginning of the winding of the bunch. 100

I have herein shown and described one practical embodiment of my invention, and various changes or modifications thereof may be made by those skilled in the art without departing from the spirit and scope of my invention. 105

Having fully described my invention, what I claim as new, and desire to secure by Letters Patent, is—

1. In a spinning-frame, a builder-motion, 110 automatically-operating controlling means therefor, including two actuating members to effect the winding of a bunch, and thereafter a main or service winding, of yarn upon a yarn-receiver, and means to vary the position of the bunch upon the yarn-receiver. 115

2. In a spinning-frame, a builder-motion, automatically-operating controlling means therefor including two actuating members to effect the winding of a bunch, and thereafter a main or service winding, of yarn upon a yarn-receiver, and means to vary the volume of the bunch. 120

3. In a spinning-frame, a builder-motion, automatically-operating controlling means 125 therefor, including two actuating members, to effect the winding of a bunch, and thereafter a main or service winding, of yarn upon a yarn-receiver, means to vary the position of the bunch upon the yarn-receiver, and 130 means to vary the volume of the bunch.

4. In a spinning-frame, a builder-motion, including a builder-arm, two followers mounted thereon, two traverse-cams rotatable in

unison, one of said cams effecting a plurality of short traverses, and the other effecting long traverse, for each complete revolution, to respectively effect the winding of a bunch, and 5 a main winding, of yarn upon a yarn-receiver, combined action of the cams at a predetermined point in their rotation effecting a change in the control of the builder-arm from the bunch-winding to the main-winding cam, 10 and means to prevent premature change of control.

5. In a spinning-frame, a builder-motion, including a builder-arm, a multiple-traverse bunch-winding cam, a long-traverse main-winding cam, a follower for each cam, carried 15 by the builder-arm, means to prevent premature engagement of the main-winding cam with its follower during the formation of a bunch of yarn upon a yarn-receiver, and an 20 adjustable governing device for said means, to render the latter inoperative when a predetermined amount of yarn has been wound in the bunch, simultaneous action of the cams upon their followers thereafter operating automatically 25 to render the bunch-winding follower inoperative, and the main-winding follower operative, to effect the main or service winding of yarn upon the yarn-receiver.

6. In a spinning-frame, a builder-motion, 30 including a builder-arm, a bunch-winding cam, a main-winding cam, a follower for each, mounted on the builder-arm, means to adjust the bunch-winding follower, to thereby vary the position of the bunch of yarn upon a yarn-receiver, and means to automatically shift the 35 control of the builder-arm, by or through their respective followers, from one to the other of said cams.

7. In a spinning-frame, a builder-motion, 40 including a builder-arm, a bunch-winding cam, a main-winding cam, a follower for each, connected rocker-arms mounted on the builder-arm, and on which the followers are supported, an adjustable connection between 45 the bunch-winding follower and its rocker-arm, whereby the position of the bunch of yarn upon the yarn-receiver may be varied, and means to shift the control of the builder-arm, by or through their respective followers, 50 from the bunch-winding to the main-winding cam.

8. In a spinning-frame, a builder-motion, including a builder-arm, a bunch-winding cam, a main-winding cam, shiftable followers 55 for said cams, mounted on the builder-arm, manually-operated means to prevent said followers from shifting when the bunch-winding cam assumes control of and actuates the builder-arm, and adjustable mechanism to 60 automatically render said means inoperative, and thereby permit shifting of the followers, when a predetermined amount of yarn has been wound in the formation of the bunch.

9. In a spinning-frame, a builder-motion, 65 including a builder-arm, a bunch-winding cam, a main-winding cam, a follower for each cam, a rock-shaft mounted on the builder-

arm and rigidly connected with the followers, a pawl-carrier pivotally connected with the rock-shaft and having a slight movement 70 relative thereto, a pawl on said pawl-carrier, a locking device to prevent movement of the latter and retain the rock-shaft from rotation, and means to automatically release the pawl-carrier when a predetermined amount of yarn 75 has been wound in the bunch, said means including a normally-rotating ratchet, the pawl intermittently engaging and arresting the ratchet while the pawl-carrier is locked.

10. In a spinning-frame, a builder-motion, 80 including a builder-arm, a bunch-winding cam, a main-winding cam, a follower for each cam, a rock-shaft mounted on the builder-arm and rigidly connected with the followers, 85 a pawl-carrier pivotally connected with the rock-shaft and having a slight movement relative thereto, an adjustable pawl on said pawl-carrier, a locking device for the latter, and means to automatically release the pawl-carrier when a predetermined amount of yarn 90 has been wound in the bunch, said means including a normally-rotating ratchet, the pawl intermittently engaging and arresting the same while the pawl-carrier is locked, adjustment 95 of the pawl operating through the ratchet to hasten or retard the release of the pawl-carrier.

11. In a spinning-frame, a builder-motion, including a builder-arm, a bunch-winding cam, a main-winding cam, a follower for each 100 cam, mounted on the builder-arm, means manually movable into position to prevent operative engagement of the main-winding cam with its follower while a bunch of yarn is laid upon a yarn-receiver, a locking device 105 to retain said means in position, and adjustable mechanism to unlock said means when a predetermined amount of yarn has been wound in the bunch, said means including a rotating disk, a trip thereon, a 110 ratchet normally rotatable with the disks, and a device to intermittently arrest the rotation of the ratchet and therethrough effect engagement of the trip and locking device, to thereby release the said manually-operated 115 means and permit shifting of control of the builder-arm from the bunch-winding to the main-winding cam, to lay a main or service winding of yarn upon the yarn-receiver.

12. In a spinning-frame, a builder-motion, 120 a bunch-winding cam, a main-winding cam, to separately effect the operation of the builder-motion, to form a bunch, and a main winding, of yarn upon a yarn-receiver, means including a member manually moved into operative position, to permit the main-winding cam to assume control of the builder-motion when a predetermined amount of yarn has been wound in the bunch, and mechanism to automatically reset the said means in condition 125 for a subsequent bunch-winding during the formation of the main winding.

13. In a spinning-frame, a builder-motion, a bunch-winding cam, and a main-winding

cam, to respectively effect the formation of a bunch, and a main winding, of yarn upon a yarn-receiver, means, including a member manually movable into operative position, to 5 permit the main-winding cam to assume control of the builder-motion when a predetermined amount of yarn has been wound in the bunch, a locking device for said member, adjustable mechanism to render the locking device 10 inoperative and thereby effect automatically the release of said member, and means to automatically reset said mechanism in readiness for the beginning of subsequent bunch-winding on a new yarn-receiver, or receivers.

15 14. In a spinning-frame, a builder-motion, automatically operating controlling means therefor to effect the winding of a bunch of yarn upon a yarn-receiver and to there- 20 after lay the yarn to form the main or serv-

ice winding, adjustable governing means to determine the amount of yarn to be laid in the bunch, and mechanism to automatically reset the governing means, during the formation of the main winding, in readiness for 25 subsequent bunch winding, said mechanism including a rotating cam-disk, a ratchet adapted to be frictionally driven by or through said disk, and co-operating devices to set the ratchet in a definite angular position relative to the disk subsequent to the change from bunch to main winding.

20 In testimony whereof I have signed my name to this specification in the presence of two subscribing witnesses.

CHARLES T. HAWLEY.
